UNITED STATES PATENT OFFICE.

EUGENE B. NOBLE, OF LOS ANGELES, CALIFORNIA.

HEAVING-PLUG.

1,212,664.

Specification of Letters Patent. Patented Jan. 16, 1917.

Application filed August 16, 1916. Serial No. 115,174.

To all whom it may concern:

Be it known that I, EUGENE B. NOBLE, a citizen of the United States, residing at Los Angeles, in the county of Los Angeles, State 5 of California, have invented new and useful Improvements in Heaving-Plugs, of which the following is a specification.

This invention relates to heaving plugs, 10 plugs for stopping wells against the upward flow of objectionable material therein, such as sand. And it is an object of this invention to provide a simple and effective form of plug which may be lowered in a well casting to any desired point and then set at 15 that point in such a manner that the upward flow and pressure will not move it.

I accomplish this object by providing a 20 plug having slips capable of expansion when the plug is struck downwardly by any suitable heavy object, such as a string of drilling tools. When once the slips are expanded they cannot be contracted by movement of the plug, and the plug is held firmly 25 against movement by the engagement of the slips with the casing.

The details of structure of a preferred 30 form of device embodying my invention, and further objects and accomplishments of my invention are explained and will be understood from the following specification, 35 reference being had to the accompanying drawings in which, for the purpose of specification, I illustrate said preferred form.

In these drawings Figure 1 is a vertical 40 longitudinal section of my heaving plug; Fig. 2 is a top view of the same, parts being shown in section on lines 2-2 of Fig. 1; Fig. 3 is a view showing the heaving plug as it is installed in a well; and Fig. 4 is a view taken as indicated by line 4-4 on Fig. 3.

In the drawings the numeral 10 designates a suitable body of metal, which may be preferably of cast iron or such material 45 as can be broken up if it is desired to remove the plug. This body has an upper circular head 11 with notches 12 in its periphery for passage of liquid. The head 11 may be of such diameter as to easily move through the 50 casing 12, not fitting the casing too closely. Below the head 11 the body 10 is formed in the manner shown in Fig. 2 with flat side surfaces 14; the body being so formed as to leave open spaces beneath the notches 12, so 55 as to provide for flow of liquid past the body.

I prefer to use three slips for holding the plug in place; although the number of slips is not a material point. The three slips 15 are mounted in vertically extending slots or 60 ways 16, one of which is shown in detail in Fig. 1. The back side of the slot 16 is provided with upwardly facing teeth 17 to be engaged by downwardly facing teeth 18 on the back edge of the slip 15. The slip 15 65 has upwardly facing teeth 19 on its outer edge; and in the normal position of the slip the teeth 19 are flush with or just behind the edge surface of the body 10, as is clearly shown in Figs. 1 and 2.

The slips normally occupy the position 70 shown in Fig. 1, near the lower end of the body. For each slip a guide rod 25 is provided to keep the slip in place with its teeth 18 engaging the teeth 17 in the body. This 75 guide rod 25 extends from top to bottom of the body parallel with the back or toothed face of slot 16. The guide rod is relatively small, and its resiliency allows the slip to move upwardly along the teeth 17, the guide 80 rod springing outwardly to allow the teeth 17 and 18 to pass each other. A compression spring 26 is placed under each slip 15 around the rod 25, tending to push the slip upwardly. A suitable means for temporarily holding the slips down is shown at 27. 85 This may consist of a short rod of easily broken material, such as a rod of cast iron small enough to be broken by a shock or jar, yet large enough to normally hold the 90 slip against the action of spring 26.

The upper end of body 10 is provided with a suitable means at 30 to which a small wire, 95 cord or rope 31 may be attached. This wire, cord or rope, or the like, is a means of suspending the heaving plug from the lower end of a string of drilling tools 32, or the like. The heaving plug having been suspended from any heavy object, it is lowered into the casing to the point at which it is 100 desired to be set. The string of tools is then allowed to drop quickly onto the plug; and the shock is sufficient to break the members 27 and allow the springs 26 to push the slips 15 upwardly. The springs need 105 not be of any greater length than necessary for merely moving the slips upwardly far enough to first engage the casing. When the slips 15 are pushed upwardly their teeth 19 engage the inner surface of the casing; and further downward movement of the body 110 of the plug then causes further expansion

of the slips 15 as they slip upwardly in the slotted ways 16. The coöperation of teeth 17 and 18 prevent the slips from moving downwardly, thus preventing the slips from contracting once they are expanded. The teeth 19 are shaped so as to positively prevent upward movement of the plug against pressure from below; and the engagement of these teeth with the casing is also sufficient to prevent the plug from slipping downwardly in the casing after it is once set. The slips are pressed outwardly with such force as to make indentations in the casing, preventing their vertical movement in the casing. The plug being set, it is only necessary to pull upwardly on the string of tools when the connecting wire or cord 31, or the member 30, will break; leaving the plug in place and allowing the string of tools to be withdrawn.

When the plug is firmly in place it cannot be moved upwardly by pressure from below; and it cannot lose its grip upon the casing on account of the teeth 17 and 18 preventing downward movement of the slips. The plug is thus immovable by the upward pressure of sand or fluid, and it prevents the upward flow of sand into the casing while allowing a sufficient flow of fluid through the openings 12.

Having described a preferred form of my invention, I claim:

1. A heaving plug comprising a body having a plurality of vertical slip ways therein, each of said ways being provided with teeth, and slips vertically movable in said ways having teeth coöperating with the teeth of the ways and having teeth for engaging a casing.

2. A heaving plug comprising a body having a plurality of vertical slip ways therein, the back wall of each of said ways extending upwardly and outwardly and being provided with upwardly facing teeth, slips adapted for vertical movement in said ways having teeth on their back faces adapted to engage the upwardly facing teeth of the ways so as to prevent downward movement but allow upward movement of the slips.

3. A heaving plug comprising a body having a plurality of vertical slip ways therein, the back wall of each of said ways extending upwardly and outwardly and being provided with upwardly facing teeth, slips adapted for vertical movement in said ways having teeth on their back faces adapted to engage the upwardly facing teeth of

the ways so as to prevent downward movement but allow upward movement of the slips, and spring means to move the slips upwardly in the ways.

4. A heaving plug comprising a body having a plurality of vertical slip ways therein, the back wall of each of said ways extending upwardly and outwardly and being provided with upwardly facing teeth, slips adapted for vertical movement in said ways having teeth on their back faces adapted to engage the upwardly facing teeth of the ways so as to prevent downward movement but allow upward movement of the slips, spring means to move the slips upwardly in the ways, and breakable means for normally holding the slips down against the upward action of the springs.

5. A heaving plug comprising a body having a plurality of vertical slip ways therein, the back wall of each of said ways extending upwardly and outwardly and being provided with upwardly facing teeth, slips adapted for vertical movement in said ways having teeth on their back faces adapted to engage the upwardly facing teeth of the ways so as to prevent downward movement but allow upward movement of the slips, spring means to move the slips upwardly in the ways, breakable means for normally holding the slips down against the upward action of the springs, and breakable suspension means for the body, so that the body may be lowered into a casing and said means broken by upward pull after the plug has been set in position in the casing.

6. A heaving plug comprising a body having a plurality of vertical slip ways therein, slips vertically movable in said ways, the outer surfaces of said slips being adapted to engage a casing, and ratchet means in the ways to prevent downward movement of the slips on the body.

7. A heaving plug comprising a body having a plurality of vertical slip ways with back walls extending upwardly and outwardly, slips vertically movable in said ways, the outer surfaces of said slips being adapted to engage a casing, and ratchet means in the ways to prevent downward movement of the slips on the body.

In witness that I claim the foregoing I have hereunto subscribed my name this 10th day of August, 1916.
